UNITED STATES PATENT OFFICE.

ALBERT A. STILLMAN, OF SYRACUSE, NEW YORK.

DENTAL TOOL-RACK AND CASE.

SPECIFICATION forming part of Letters Patent No. 313,382, dated March 3, 1885.

Application filed June 26, 1884. (No model.)

To all whom it may concern:

Be it known that I, ALBERT A. STILLMAN, of Syracuse, in the county of Onondaga, in the State of New York, have invented new and useful Improvements in Dentists' Tool-Racks and Cases, of which the following, taken in connection with the accompanying drawings, is a full, clear, and exact description.

This invention consists in a novel construction and combination of parts which in one respect perform certain functions independent of each other, but in other respects contribute to the efficiency of each other, and the whole constitute a combined cotton and floss holder and a support for a dental tool-rack, combined in a most convenient, compact, and substantial manner, as hereinafter more fully described, and specifically set forth in the claim.

20 In the annexed drawings, Figures I and II are respectively plan and front views of my invention; Fig. III, a longitudinal section of the same; Fig. IV, a transverse section on line $x x$, Fig. III; and Fig. V, an end view of 25 the cap of the cotton-holder.

Similar letters of reference indicate corresponding parts.

A represents the bed of the tool-rack, consisting of an elongated plate provided on its 30 back edge with an upwardly-turned longitudinal flange, c , against which the end of the tool-points abut, as indicated by dotted lines in Fig. I of the drawings. Upon said bed is secured a plate, B, which has projecting upward from it a row of lugs, $a a$, and a row of pins, $b b$, the lugs being arranged proper distances apart to receive in the interstices the tool-points, which are detached from the handle when placed on the rack, and when placed 40 as aforesaid the pin b enters a hole in the side of the tool-point, and thereby retains the latter while withdrawing from it or applying to it the handle of the tool or instrument.

C and C' represent the cases or receptacles 45 for the cotton and floss used in dentists' business. Said cases I form of a metal tube, in which I secure a partition separating said cases, as shown in Fig. IV of the drawings. and to the two ends of said tube I apply removable caps g and n . The cap g of the case C has an aperture, d , through which to ex-

tract the cotton from the case, and from said aperture extends a slot, h , in which lies a rod, f , which reaches into the case the entire length thereof, and is provided at its inner end with a disk or follower, e . By drawing said rod outward the cotton is forced toward the cap g of the case and caused to protrude through the aperture d sufficiently to enable the operator to grasp with his fingers some of the cotton and extract the desired amount from the case. The rod f , lying in the slot h , leaves the aperture d unobstructed. The cap g is made removable from the case to admit of replenishing the latter—to wit, the cap n of the case C' has inside of the said case a plate, u , provided with a central hole for the reception of one of the pivots of the spool m , which is removable in the extension C' and pivoted to the partition of the tube, as illustrated in Fig. III of the drawings.

On the spool m is wound the floss used in dentistry, the free end of said floss passing out through a slot, l , in the side of the case-extension C'. To the exterior of said extension is attached a knife, k , by which to sever the length of floss desired.

D D represent brackets by which to attach the case C to the usual dentist's stand, said brackets being in the form of metal bands 50 which embrace the case C and terminate with attaching-arms, as shown in Fig. IV of the drawings.

The described tool-rack and case are firmly united by the bed A of the rack being 55 mounted on the brackets D D over the case C and secured in position by screws s , passing through the bed A and through the brackets D D and into the case C, as shown.

It will be observed that by the described construction and arrangement of parts the tube of which the cases C and C' are formed is made to constitute a stiff and substantial support for the tool-rack, and the two cases or receptacles C and C' are formed by simply 95 securing a partition in the tube and placing the removable caps g and n on the ends of the tube.

Having described my invention, what I claim as new is—

100 The combination of the tube C C', provided with a partition and with a slot, l , the cap n ,

removably applied to one end of the tube, the cap *g*, removably applied to the opposite end of the tube and provided with the aperture *d*, and the spool *m* and rod *f*, respectively, 5 in opposite ends of the tube, all constructed and combined substantially in the manner set forth and shown.

In testimony whereof I have hereunto signed

my name and affixed my seal, in the presence of two attesting witnesses, at Syracuse, in the county of Onondaga, in the State of New York, this 19th day of June, 1884.

ALBERT A. STILLMAN. [L. S.]

Witnesses:

F. H. GIBBS,

C. H. DUELL.
